Primary Examiner — Mark Goodwin(57) **CLAIM**

The ornamental design for a work vehicle boom, as shown and described.

DESCRIPTION

FIG. 1 is a rear bottom perspective view of a work vehicle boom embodying the claimed design.

FIG. 2 is a left side view thereof.

FIG. 3 is a right side view thereof.

FIG. 4 is a front view thereof.

FIG. 5 is a rear view thereof.

FIG. 6 is a top plan view thereof; and,

FIG. 7 is a bottom plan view thereof.

The claimed design is shown in solid lines in the drawings. The portions of the drawings shown in broken lines form no part of the claimed design. The portions of the drawings shown in broken lines having unequal segments illustrate the boundary of the claimed design and form no part of the claimed design. The present disclosure relates to a boom arm for a work vehicle, such as a skid steer loader.
